UNITED STATES PATENT OFFICE

ERIK EMANUEL ERICSSON, OF OREBRO, SWEDEN

MEANS FOR FIXING THE BLADES OF SCYTHES TO THE SNATHS

Application filed December 4, 1929, Serial No. 411,639, and in Sweden July 23, 1929.

This invention relates to a simple and reliable device for fixing the blade of scythes and like to the snath. According to the invention the tongue of the blade is slid into a turnable holder provided on the snath or into a mounting in such a position that the tongue, as the blade is swung into its operative position on the snath is jammed by means of a coupling device comprising for instance a notch or a groove provided in the tongue and a projection or flange provided in the holder or the mounting. The blade is locked in the said position by a bolt or catching device of suitable construction.

The invention is illustrated in the accompanying drawings. Fig. 1 shows in a side view a blade, the tongue of which is provided with a notch for the connecting of the blade with the snath in accordance with this invention. Fig. 2 is a view of a turnable holder for the blade. Figs. 3 and 4 are sections on the lines A—B and C—D respectively in Fig. 2. Fig. 5 is a longitudinal section of a mounting for the holder. Fig. 6 is a section on the line E—F in Fig. 5. Fig. 7 shows in a section the mounting and the holder pivoted to the same and also the blade located in the holder and locked in operative position. Fig. 8 shows in a side view the holder located in the mounting and turned to its locked position. Fig. 9 shows in a side view a blade, the tongue of which is provided with a lateral groove adapted to engage a flange provided in the holder or the mounting for fixing the blade. Fig. 10 shows in a side view a holder for the blade shown in Fig. 9. Fig. 11 is a section on the line G—H in Fig. 10. Fig. 12 shows in a longitudinal section a mounting for the said holder. Fig. 13 is a side view of the mounting partly in section.

notch 3 is provided in the tongue for the fixing of the blade in a holder 4, shown separately in Figs. 2 to 4 inclusive and in combination with other members as shown in Figs. 7 and 8. The said holder has a U-shaped cross-section for instance, one 5 of its flanges having an inner projection 6. The opposite flange 7 is shorter than the flange 5, so that the holder is open opposite to the said projection 6, Fig. 4. The holder tapers toward the end at which the projection is located, as seen from Fig. 2. The holder 4 is by means of a pin or rivet 8 turnably connected to a tongue 9 of a sleeve shaped mounting 10, which is adapted to be slid on the snath and fixed to the same. 11 is a bolt, slideable in the mounting 10 and held in the shown operative position by a spring 12, bearing against a flange of the bolt and a pin 13 screwed into the mounting.

For the fixing of the blade to the snath the holder 4 is brought into an oblique position with relation to the mounting with its wider end directed outwards. The tongue 1 of the blade is slid into the holder in the direction indicated by the arrow, Fig. 2, and with the notch 3 facing the flange 5 provided with the projection 6. After the tongue 1 has been slid into the holder, the notch 3 is located substantially opposite to the projection 6. As the blade occupies the said position it is swung inwards towards the snath, during which operation the holder is turned on the pin 8 and the bolt 11 is kept in its inner position by the holder. As the blade occupies its operative position with relation to the snath, the bolt 11 is forced outwards by the spring 12 and locks the holder 4, Figs. 7 and 8. While the blade is swung into its operative position, during which operation the back of the tongue bears against the flange 7, the

45 Figs. 14 and 15 show in a longitudinal section and in a side view respectively a mounting adapted for the fixing of the blade directly to the same; Fig. 14 is a section on the line I—K in Fig. 15. Fig. 16 shows in a perspective view a blade fixed to a snath by means of the device illustrated in Figs. 14 and 15.

The tongue 1 of the blade 2 shown in Fig.

the tongue bears against the flange 7, the notch 3 of the tongue 1 engages the projection 6 at its outer, preferably rounded corner *a*, so that the tongue is positively drawn into the holder and in consequence of the tapering shape of the tongue and the holder is jammed in the latter. As the blade is in its operative position the holder bears against the mounting and the bolt and besides the tongue bears

The tongue 1 of the blade 2 shown in Fig. 100 extends longitudinally of the blade. A

and also against the mounting by means of its back.

Consequently, the blade is rigidly fixed to the snath without any possibility of getting loose. After the tongue has been slid into the holder the blade is fixed through a single turning operation, for which reason the fixing of the blade is exceedingly simple. For the removing of the blade the bolt 11 is forced inwards by means of a finger and the blade together with the holder then turned outwards, the blade being finally disengaged from the projection 6.

In the connection device shown in Figs. 10 to 13 inclusive the U-shaped holder 14, tapering toward its one end, is turnable on a pin 15 fixed in a mounting 16. The said mounting is provided with a bolt 17. The tongue 20 of the blade 18, Fig. 9, adapted to be fixed by means of the device shown in Figs. 10 to 13 inclusive, is provided with a lateral groove 19. The said groove 19 is adapted to co-operate with a flange 21 provided in the mounting 16. In order that the said flange 21 may not prevent the holder from being turned, an opening 22 is provided in one of the flanges of the holder.

The tongue 20 of the blade 18 is slid into the holder 14 and the blade together with the holder is then turned toward the snath. During the said operation the lateral groove 19 engages by means of its rounded corner *b* the rounded corner *e* of the flange 21, which results in the tongue 20 being drawn into the holder 14 and jammed in the same. After the blade has arrived to its operative position, the bolt 17 is forced outwards and locks the holder. Also in this case the blade is fixed through a single turning of the blade. The disengaging of the blade is easily effected after the bolt 17 has been forced inwards and the blade swung outwards.

Figs. 14, 15 and 16 show the most simple form of execution of the invention. In the present form of execution the holder is omitted and the blade is fixed by the tongue engaging directly the mounting 23 fixed to the snath 28 by screws or the like. The tongue is provided with a lateral groove in accordance with Fig. 9, which co-operates with a flange 22 provided in the mounting 23. 24 is a bolt provided in the mounting. The mounting 23 has a sleeve shaped part 25, which is located transversely to the mounting 25 and in which the flange 22 is provided. A lateral opening 26 is provided in the sleeve-shaped part 25 leaving a wall 27 at this side of the part. 29 are the nibs of the snath 28.

The tongue of the blade is slid into the sleeve shaped part 25 of mounting 27 in the direction indicated by the arrow in Fig. 15 and is then swung toward the snath. The lateral groove of the tongue then engages the flange 22, while the tongue bears against the wall 27. The tongue is drawn into the sleeve

shaped part 25 of the mounting through the co-operation of the lateral groove and the flange 22 and is jammed in the said part. The blade is locked in its operative position by the bolt 24.

The invention may evidently be modified in some respects without exceeding the limits of the same. For instance the projection or flange of the coupling may be provided on the tongue of the blade and the notch or groove in the holder or mounting as easily understood by those skilled in the art.

I claim:

1. Means for fixing to the snath the blade of a scythe or the like having a tapering tongue, characterized by a member provided on the snath and shaped in accordance with the said tongue and having engaging means carried thereby, which is adapted after the insertion of the tongue into the said member and at turning the blade into its operative position to engage corresponding engaging means on the tongue and to effect a sliding movement of the tongue, so that the latter is jammed in the member, and a catching device, which locks the blade in the said position.

2. Means for fixing to the snath the blade of a scythe or the like having a tapering tongue, characterized by a holder, turnably mounted on the snath and shaped in accordance with the said tongue and having engaging means carried thereby, which is adapted after the insertion of the tongue into the said holder and at turning the blade into its operative position to engage corresponding engaging means on the tongue and to effect a sliding movement of the tongue, so that the latter is jammed in the holder, and a catching device, which locks the holder, as the blade is in its operative position.

3. Means for fixing to the snath the blade of a scythe or the like, having a tapering tongue, characterized by a mounting fixed to the snath and shaped in accordance with the said tongue and having engaging means carried thereby, which is adapted after the insertion of the tongue into the said mounting and at turning the blade into its operative position to engage engaging means on the tongue and to effect a sliding movement of the tongue, so that the latter is jammed in the mounting, and a catching device which locks the blade in the said position.

4. A scythe-blade having its tongue located substantially longitudinally of the blade and provided at one of its longitudinal edges with an engaging device so shaped that, as the blade and a corresponding engaging device on the snath are brought together, and the blade turned into its operative position transverse to the snath the blade is shifted with relation to the snath and jammed to the same.

5. A scythe-blade having its tongue lo-

cated substantially longitudinally of the blade and provided in one of its longitudinal edges with a transverse recess so shaped that as the blade and a corresponding engaging device on the snath are brought together 5 and the blade turned into its operative position transverse to the snath the blade is shifted with relation to the snath and jammed to the same.

In testimony whereof I have hereunto affixed my signature.

ERIK EMANUEL ERICSSON.
